UNITED STATES PATENT OFFICE.

ULRICH EBERHARDT AND HENRY E. EBERHARDT, OF NEWARK, NEW JERSEY.

PLATE-PRINTING MACHINE.

SPECIFICATION forming part of Letters Patent No. 403,181, dated May 14, 1889.

Application filed May 3, 1888. Serial No. 272,621. (No model.)

To all whom it may concern:

Be it known that we, ULRICH EBERHARDT and HENRY E. EBERHARDT, citizens of the United States, residing, respectively, at Newark, Essex county, New Jersey, have invented 5 certain new and useful Improvements in Plate-Printing Machines, fully described and represented in the following specification and the accompanying drawings, forming a part of the 10 same.

This invention relates to sundry details of construction in plate-printing presses, whereby the cost and labor of constructing the machine are materially simplified and the operation of the machine is rendered more certain 15 and more perfect.

The improvements consist partly in the construction of the gearing for actuating the driving-chain, partly in the construction of 20 the pad-pressers, partly in the construction of the adjustable eccentrics for vibrating the pad-holder, partly in the feeding devices for moving the wiper-cloth at intervals over the pad, partly in the construction of buffers at 25 the corners of the machine, and partly in the means for regulating the rotations of the impression-roller.

These improvements will be understood by reference to the annexed drawings, in 30 which—

Figure 1 is an elevation of one side of the machine, showing the improved gearing and the cloth-feeding devices. Fig. 2 is an inside view of the device for tripping the feed-latch. 35 Fig. 3 is a plan of the frame with the impression-roller and all its fixtures removed, the inking-fixtures removed, and the four planks or tables with their driving-chain omitted from the view, so as to expose clearly to view 40 the improved mechanism for driving the chain. Fig. 4 is a sectional elevation on line xx in Fig. 3, only the frame being shown in section and the impression-roller being exhibited with one of the planks carrying a plate 45 in contact with the same. Fig. 5 is an edge view of the pad-holder. Fig. 6 is a plan of the same holder, and Fig. 7 is a transverse section on line yy in Fig. 6. Fig. 8 is a side view, and Fig. 9 a plan, of the adjustable eccentric- 50 pin for vibrating the pad-holder. Fig. 10 is a plan, and Fig. 11 a side view, of the shaft and

plate for driving the same. Fig. 12 is an enlarged view of one of the friction-drivers for the wiper-cloth, and Fig. 13 is a central transverse section of the same with the end of its 55 shaft not in section. Fig. 14 is a side view of one of the detachable feed-wheels. Fig. 15 is a side view, and Fig. 16 an edge view, of the segmental brake for the impression-roll. In Figs. 1 and 4 the lower part of the frame is 60 omitted to avoid reducing the scale of the drawings, and Figs. 5 to 16, inclusive, are drawn upon a larger scale than the previous figures to show the details of construction 65 more clearly. Fig. 17 shows a housing with dash-pot attached.

In plate-printing machines a rectangular frame, A, is employed, as shown in Fig. 3, provided along its four sides with ways B, to guide the planks C (shown only in Fig. 4) 70 from the inking-roll to the wiping and printing devices, the inking-rollers being located between the pressing-rollers and the wiping-rollers, as at I in Fig. 3. To move the planks along the ways and to shift them automatically at the corners of the frame, an endless chain is commonly employed and actuated by one or more sprocket-wheels located near the corners of the frame and propelling the chain along the four sides of a rectangle. In Fig. 80 3 two of such sprocket-wheels D are shown mounted upon shafts D', and two idler-pulleys, D², are shown at the opposite side of the frame, around which the endless chain would be passed; but the chain is omitted from the 85 drawing, as its operation is already well known in the art, as is shown in United States Patent No. 180,490, dated August 1, 1876.

In order to drive the two sprocket-wheels D, it has been common heretofore to connect 90 them together and to the driving-shaft of the machine by a large number of bevel-wheels, which require bearings at right angles to one another and careful adjusting to bring the teeth into proper contact.

In our construction we apply spur-wheels f to each of the shafts D', making such wheels of sufficient size to mesh with a single intermediate spur-wheel, f' . This wheel is sustained upon a stud, g , midway between the 100 shafts D', with one edge adjacent to one of the shafts a , which drive the eccentric-pins a'

to vibrate the wiper-frame. The shafts a are driven by bevel-wheels g^2 thereon, meshing with similar wheels, g^2 , applied to the main shaft f^2 , which is extended beneath the frame and provided with a driving-pulley, f^3 , as shown in Fig. 4, and the mere application of a spur-pinion, g' , to one of these shafts then suffices to drive both the chain-wheels D by its contact with the intermediate spur-wheel, f' .

10 The shafts a extend above the frame A and are provided upon the top with plates b , to which are fitted movable plates b' , carrying the eccentric-pins a' . Heretofore the eccentric-pins have been fitted by a head at their 15 lower end, movable in slots formed in the plates b ; but in our construction the pins are fixed rigidly in movable plates, which thus give them a broad foothold by which they may be securely bolted upon the rotating 20 plates b when adjusted.

The plates are shown in detail in Figs. 8 to 11, inclusive, the plate b having slots c , and the plates b' having tap-holes c' , with bolts d (shown only in Figs. 1 and 4) inserted through 25 the slots and screwed tightly into the holes c' to hold the movable plates in the desired eccentric position.

The plates are both shown grooved in Fig. 4, with a key, d' , fitted to the grooves; but a 30 groove is shown only in the plate b in Fig. 11, and the key d' formed upon the plate b' to fit the same. By this construction the eccentric-pins are held very rigidly when adjusted. The keys d' maintain their parallelism in all 35 positions, and when lined with one another may be simultaneously adjusted in their desired eccentric position and secured therein by tightening the bolts d .

In Figs. 5 to 7 the pad-frame E is shown 40 enlarged with four T-shaped bars fitted longitudinally within its open bottom to press by their weight upon the pad H . The T-bars are formed each with a central rib, E' , fitted to grooves e' , formed vertically inside the ends 45 of the frame E , and the lower faces of the T-bars consist in flat plates adapted to bear upon the pad H and to press the wiper-cloth upon the engraved plate. The pad is held at its opposite ends in clamps h , secured to 50 hanger-bolts h' , which are extended through flanges or ears h^2 , formed upon the sides of the pad-frame, and the bolts are provided with thumb-nuts i , by which they may be drawn up at pleasure, and the pad thus be 55 readily tightened with the required tension.

In Fig. 1 the feed-rollers o for the rag or wiping-cloth are shown mounted in bearings above the pad-frame, with a roll of cloth, p , and a winding-roller, p^{10} , which latter is driven 60 by pulleys r and a belt, r' , receiving motion from one of the cloth-rollers. The feed-rollers are provided at their outer ends with friction driving-disks o' , clamped one on each side upon sprocket-wheels s , which are driven 65 continuously by a chain, s' , from a wheel, s^2 . (Shown in Fig. 4 as actuated by a shaft, s^3 , and bevel-wheels s^{40} .) One of the driving-

disks is provided with a sleeve, o^2 , fitted longitudinally to a key, o^3 , upon the shaft o^4 of the feed-roller, and the sprocket-wheel s is 70 pressed between the disks by a nut or collar, j , fitted to a screw-thread upon the outer end of the sleeve. Layers of leather, k , are inserted between the disks and wheel s to increase the friction, and the collar j is split at 75 one side and clamped upon the sleeve by a screw to hold it in the desired position when the disks are clamped with the desired force upon the sprocket-wheel. The rag or cloth p is conducted from the roll p^4 under guide-roller p^2 , and thence over the feed-roller o and downward across the pad to the feed-roller o^6 , whence it passes under another guide-roll, p^3 , to be wound upon the winding-roll p^{10} . The feeding-roller first receiving the 85 rag is provided with an automatic feeding device, which permits its rotation only at regular intervals, which are regulated by the movement of a pawl or latch engaging a ratchet-wheel rotating with the shaft of such 90 roll.

The continuous motion of the chain s' causes the sprocket-wheels upon both the feed-rollers o and o^6 to rotate continuously, while the disks o' upon the shaft of the first roll are 95 held by the ratchet from rotation intermittently, thus holding back the cloth from the take-up device. The second feed-roller is not, however, restrained by any ratchet, but is rotated independently by its own friction-driver, and tends by its frictional contact with the wiper-rag p to draw the same tightly across the face of the pad.

The ratchet k' is shown in Fig. 13 provided with holes k^2 , fitted to pins upon one of the 105 disks o' , and secured removably to such disk, and a latch, l , (shown in Figs. 1, 3, and 4,) is pivoted upon the pad-frame to hold the ratchet and the cloth-roll to which it is attached from rotation. A rod, l' , is attached 110 to the latch and extended through a guide, l^2 , upon the bearing of the shaft s^3 , and is provided with a toe or collar, l^3 , arranged in the path of a dog, l^4 , upon one side of the sprocket-wheel s^2 , and the dog operates at each 115 rotation of such sprocket-wheel to draw the rod slightly downward and to pull the hooked end of the latch out of the ratchet-teeth.

A spring, l^5 , operates normally to lift the rod and hold the latch into the ratchet, and 120 one tooth of the ratchet is therefore released at each rotation of the wheel s^2 . The feed-roller to which the ratchet is attached is thus permitted to make a part of a revolution, which feeds the cloth forward a little and 125 slackens the wiper-cloth upon the face of the pad, and the slack of the cloth is then immediately taken up by the friction of the other feed-roller and by the winding-roller p^{10} .

The essential part of this improvement is 130 the continuously-rotating friction-driver operating upon the feeding-roller intermittently by the action of a ratchet-wheel and intermittently-operating pawl or latch. The sleeve

and friction-driver on such feed-roller may be removed from the shaft by detaching a pin, c^3 , (shown in Fig. 13,) for the purpose of changing the ratchet-wheel, and a series of ratchet-wheels may thus be used with different numbers of teeth to produce a greater or less rotation of the feeding-roller for each actuation of the pawl or latch l .

Upon the forward end of the shaft s^3 is shown a weighted lever, s^4 , provided with an idler-pulley, s^5 , which is pressed by the lever against the chain s' and operates to take up the slack of the chain in its motion around the wheels s and s^2 when the wiper-frame is vibrated by the crank-pins a' .

The improvement in the buffers consists in providing a strip of wood at the forward end of each of the "ways" in which the planks move, so that as the planks reach each corner of the frame their momentum may be arrested without shock. The buffers may, if desired, be also provided at the rear end of each of the ways, as the rear corner of each plank is liable as the planks move from one of the four sides of the frame to the adjacent side to be twisted around into contact with the side of the ways, and the wood may therefore with advantage be used at both ends of each of the ways, as is shown in Fig. 3. To introduce such wooden strips, the outer flange of the ways (lettered B' in Fig. 3) is notched out, as indicated at B^3 in Fig. 1, and the strips of wood B^3 are inserted in such notches. To render the wood more yielding under the impact of the planks, we prefer to attach the wooden strips by screws b^6 to the upper edge of the spring-plates B^4 , which are attached to the outside of the frame by bolts b^5 . The pressure upon the wood causes such spring-plates to slightly yield above the point held by the bolts b^5 , and the planks are thus brought to rest with very little concussion. In practice the strips of wood B^3 would not project materially beyond the line of the ways; but they are shown in Fig. 3 projected somewhat within the flanges B' to distinguish them clearly from the latter.

Figs. 15 and 16 show a segmental brake, t , applied to one end of the pressure-roll, and Fig. 17 shows a weight, K , attached by a cord, K' , to one end of the blanket J , which is wrapped around the impression-roll P , as is usual.

One of the housings P' for the impression-roll is shown in Fig. 17, with a dog, w , attached to the end of the roller, and operating with the stop w' upon the housing to check the motion of the roll when reversed by the weight K after each impression.

It is desirable in printing that the weight should bring the dog always into contact with such stop, so that the impression may always commence at the same point upon the roll P ; but no means has been heretofore found for bringing the roll to rest exactly in contact with such stop, as the elasticity of the parts

tends to produce some recoil. To prevent such recoil is the object of the segmental brake and of a dash-pot attachment, which are shown in Fig. 4 applied to the opposite ends of the impression-roll. This attachment consists in a dash-pot, v , attached to the housing P' or any other fixed point upon the frame A , and having its plunger v' actuated by a rack, u , which is reciprocated by a pinion, u' , upon the shaft P^2 of the impression-roll. Such dash-pot, if made deep enough to retard the motion of the roll P during a considerable part of its rotation, would prevent the quickness of movement that is desired, and it is therefore made comparatively shallow and adapted only to assist (at the end of the reversing movement) the operation of the segmental brake t . This brake consists in a segmental tongue, t , formed upon a hub, t^4 , attached to the shaft P^2 , and arranged to enter between clamp-plates t' during the reversal of the roll P , and to gradually check the motion of the roll by its friction against such plates. The brake also resists the forward movement of the roll P ; but this is of no consequence, as such roll is driven forward by the friction of its surface with the plate upon the moving plank and readily overcomes the frictional resistance of the brake. The plates are secured together at their opposite ends by studs or bolts t^5 , which hold them stationary upon the housing P' , and one of the clamp-plates is adjustable toward the other by means of nuts t^6 . The inner sides of the plates are preferably provided with a facing, t^7 , of leather, to form a suitable friction-surface to bear upon the segmental tongue t , and the ends of the latter are tapered to make them enter readily between the clamp-plates.

The segmental brake or tongue is shown in Fig. 15 occupying about half a circle, and the brake thus operates to retard the momentum of the roll for a considerable part of its rotation, while the plunger v' , being thrust into the dash-pot by the rack u near the close of the reverse movement, brings the roll to rest at the desired point.

The combined operation of the dash-pot and brake is regulated by the pressure of the clamp-plates t' upon the brake, which can be effected by adjusting the nuts t^6 while the machine is in operation, so as to secure exactly the desired result. By this construction the dog w , rotating with the impression-roll, may be brought to a gradual and complete contact with the fixed stop w' when reversed by the weight K after each impression, and the recoil of the roller from such stop may be wholly prevented.

The actuation of the winding-roller by a continuously-rotating friction-driver keeps the rag p tightly stretched across the face of the pad during the whole time the machine is in operation, and thus completely prevents the formation of any wrinkles in the rag, which

are liable to occur with other constructions, and which are very detrimental to the clean wiping of the engraved plate.

We hereby disclaim the broad combination, 5 in a printing-machine wherein the bed or plank travels in a polygonal path, of a bed and a cushioning apparatus located adjacent to the point where the travel of the bed is changed in direction, or any similar combination in 10 which the cushioning apparatus is provided with a contacting-piece against which the bed contacts as it moves in one direction, along which it slides as it moves away therefrom.

We also disclaim the combination, with 15 the **D**-roll and a bed traveling thereunder, of the blanket attached to the roll, the weight to unwind the blanket, and the dash-pot to aid in checking the momentum of the weight; also, the combination, in a plate-press, of a 20 traveling bed, a **D**-roll above the same, a blanket attached at one end to said roll, a weight connected to said blanket and tending to unwind the same, and the spring-brake acting in connection with a suitable projection 25 to check the roll in its backward motion.

Having thus set forth our invention, what we claim herein is—

1. In a plate-printing press, the combination, with the horizontal driving-shaft f^2 and 30 the sprocket-wheel shafts D' , of the spur-wheels f , the spur-wheel f' , intermediate to the same, and the pinion g' , driven by the bevel-wheels g^2 , substantially as herein set forth.

2. In a plate-printing press, the combination, with the horizontal driving-shaft f^2 and 35 the sprocket-wheel shafts D' , of the shafts a , for driving the crank-pins a' , the bevel-wheels connecting such shafts with the main shaft f^2 , the spur-wheels f upon the sprocket-wheel 40 shafts, the spur-wheel f' , intermediate to the same, and the pinion g' , applied to one of the shafts a to drive the intermediate wheel, as and for the purpose set forth.

3. In a plate-printing-machine, the combination, with the pad-frame E , provided internally with the grooves e , of the T-shaped presser-bars provided with rib E' , fitted to such grooves and movable vertically within the pad-frame, as and for the purpose set 50 forth.

4. In a plate-printing machine, the combination, with the pad-frame E and the pad H , of clamps h , secured to the opposite edges of the pad, and the hanger-bolts h' and nuts fitted upon the pad-frame to tighten the pad, substantially as set forth.

5. In a plate-printing machine, the combination, with the eccentric-shafts a and the disks b , fixed thereon, of the disks b' , provided with the crank-pins a' , the key d' , for guiding one disk upon the other, and the bolts d , for clamping the disks when adjusted, as and for the purpose set forth.

6. In a plate-printing machine, the combination, with the pad-frame, the pad, and the wiper rag or cloth, of two feed-rollers for the wiping-cloth, provided each with a continu-

ously-rotating friction-wheel, and a ratchet with latch for intermittently releasing one of such rollers, as and for the purpose set forth. 70

7. In a plate-printing machine, the combination, with the pad-frame, the pad, and the wiper-cloth, of a feed-roller rotated intermittently to feed the cloth beneath the pad, a feed-roller rotated continuously upon the cloth 75 at the opposite side of the pad, and a winding-roller for winding up the cloth, as and for the purpose set forth.

8. In a plate-printing machine, the combination, with the pad-frame, the pad, and the 80 wiper-cloth, of two feed-rollers provided each with a continuously-rotating friction-wheel, a ratchet-wheel fixed removably upon one of the rollers, and a latch held normally in the teeth of such ratchet-wheel and intermittently drawn therefrom, as and for the purpose 85 set forth.

9. In a plate-printing machine, the combination, with the pad-frame, the pad, and the wiper-cloth, of two feed-rollers for winding 90 cloth, provided each with friction clamping-disks, a sprocket-wheel clamped between said disks, a chain provided with a tightener and rotating such sprocket-wheels continuously, a ratchet-wheel fixed upon one of such rollers, and a latch operating to intermittently release the ratchet, as and for the purpose 95 set forth.

10. In a plate-printing machine, the combination, with the frame A and the ways B , 100 formed parallel with the four sides of the frame, of the planks C , propelled in such ways as set forth, the spring-plates affixed to the frame at the forward ends of the ways, the notches cut in the frame, and the wooden 105 blocks secured to the spring-plates and operating as a buffer for the planks C , substantially as herein set forth.

11. In a plate-printing machine, the combination, with the compression-roll P and a 110 blanket, J , operated normally to reverse the roll after each impression, of the segmental brake t , formed with tapering ends and attached to the roll-shaft P^2 , and the stationary friction-clamps t' , adapted to admit the brake 115 and to grasp the same elastically, as and for the purpose set forth.

12. In a plate-printing machine, the combination, with the impression-roll P and a 120 blanket, J , operating normally to reverse the roll after each impression, of the segmental brake t , formed with tapering ends and attached to the roll-shaft P^2 , and the stationary clamp-plates t' , with leather facing t^3 and adjustable toward one another by the bolts provided with nuts t^3 , as and for the purpose 125 set forth.

In testimony whereof we have hereunto set our hands in the presence of two subscribing witnesses.

ULRICH EBERHARDT.
